RECEPTACLE-EMPTYING DEVICE

Edgar M. Valleroy, St. Louis, Mo., assignor, by mesne assignments, to Edgar La Mear, St. Louis County, Mo.

Filed Aug. 15, 1956, Ser. No. 604,100

9 Claims. (Cl. 214—302)

This invention relates to receptacle-emptying devices, and more particularly to a vehicle-mounted device for lifting a rubbish receptacle and dumping the rubbish into the vehicle.

Among the several objects of the invention may be noted the provision of a device of the class described for use on the side of a vehicle, and particularly a drum-type sanitation hauling truck having a side opening for loading, for lifting up a rubbish receptacle on the side of the truck and tilting the receptacle to discharge its contents through the side opening and into the drum of the truck; the provision of a device of this class which enables the rapid and economical emptying of large heavy containers, which may weight twenty-five hundred pounds or more when empty; and the provision of a device of this class which is of economical construction and hydraulically powered from the hydraulic power system conventionally provided on vehicles of the class described. Other objects and features will be in part apparent and in part pointed out hereinafter.

The invention accordingly comprises the constructions hereinafter described, the scope of the invention being indicated in the following claims.

In the accompanying drawings, in which one of various possible embodiments of the invention is illustrated, FIG. 1 is a side elevation of a vehicle equipped with a receptacle-emptying device of this invention;

FIG. 2 is an enlarged horizontal section taken on line 2—2 of FIG. 1;

FIG. 3 is an enlarged vertical transverse section taken on line 3—3 of FIG. 1 illustrating in solid lines a lowered position of the device and in dotted lines an intermediate raised position of the device preliminary to tilting of the receptacle; and,

FIG. 4 is a view similar to FIG. 3 illustrating the device in a position wherein the receptacle is tilted.

Corresponding reference characters indicate corresponding parts throughout the several views of the drawings.

Referring to the drawings, there is indicated at 1 in FIG. 1 a typical drum-type sanitation hauling truck of the type on which a receptacle-emptying device of this invention is used. The truck has a drum 3 which is adapted to be tilted from a horizontal loading position for rearward dumping, the drum 3 having a pivoted rear end gate 5. The drum has a side opening 7 toward the front for loading it. It will be understood that rubbish dumped into the drum through the loading opening 7 is pushed toward the rear and compacted by a piston (not shown).

There is indicated at 9 in FIGS. 3 and 4 a rubbish receptacle or bin of a type such as is used in large housing projects. This bin consists of a rectangular steel box mounted on casters 11 so that it may be readily rolled to the curb C for being emptied into a truck. It has doors 13 in the top for dumping rubbish into it, and a pivoted gate 15 at one end. This gate is pivoted at its top to the bin 9, as indicated at 17. Suitable means such as indicated at 18 is provided for latching the gate 17. To adapt the bin for being handled by the emptying device of this invention, it is provided on both sides thereof with pins such as indicated at 19 for attachment of chains, as will be made clear, and at its gate end with bottom hooks such as indicated at 21.

2

For lifting a bin 9 and tilting it to discharge rubbish therefrom through opening 7 into the drum 3, the truck 1 is provided with a U-shaped boom generally designated 23 having extensible sides. Each side of the boom is 5 constituted by a fluid pressure cylinder designated 25, more particularly a hydraulic cylinder. These hydraulic cylinders are mounted for swinging movement in vertical planes on opposite sides of the opening 7 on a horizontal axis extending lengthwise of the truck below the opening 7. For this purpose, each cylinder 25 at one end (its inner end) has a pin connection indicated at 27 with a bracket 29 attached to the drum 3. Each cylinder has a plunger 31 which extends out of its other end and outer end, the outer ends of the two plungers 31 being connected by a crossbar 33. Attached to the crossbar 33 are two pairs of chains 35, one pair of chains being for connection to the pins 19 on one side of a bin, the other pair being for connection to the pins 19 on the other side of the bin.

20 Means indicated generally at 36 is provided on top of the drum 3 for swinging the boom 23 from a lowered position such as shown in solid lines in FIG. 3 to the intermediate raised position such as shown in dotted lines in FIG. 3 and the final position such as shown in FIG. 4.

25 This means includes a box 37 mounted on top of the drum 3 extending lengthwise of the drum across the top of the opening. It comprises a fluid pressure (hydraulic) cylinder 39 (see FIG. 2) fixed on the bottom of the box extending lengthwise in respect to the drum 3. The cylinder 39 has a piston 41. A piston rod 43 extends rearward in respect to the drum 3 from the piston out of the rearward end of the cylinder. On the rearward end of the rod 43 is a block 45. This carries a transverse horizontal shaft 47. Two pulleys 49 and 51 are mounted

30 on the shaft on one side of the block and two pulleys 53 and 55 are mounted on the shaft at the other side of the block. At the forward end of the cylinder 39 are bracket arms 57 carrying a horizontal shaft 59. Two pulleys 61 and 63 are mounted at one end of the shaft 40 and one pulley 65 is mounted at the other end of the shaft. A cable 67 is anchored at one end as indicated at 69, trained around the pulleys 49, 61, 51 and 63, then passes around a pulley 71 mounted on a vertical shaft 73 extending up from the bottom of the box, thence 45 out of the box through a side opening 75 in the box at the rearward side of opening 7, and thence through a guide 77 on the drum to a connection indicated at 79 with the crossbar of the boom. A cable 81 is anchored at one end as indicated at 83, trained around the pulleys 53, 65 and 55, then passes around a pulley 85 mounted on a vertical shaft 87 extending up from the bottom of the box, thence out of the box through a side opening 89 in the box at the forward side of opening 7, and thence 50 through a guide 91 on the drum to a connection indicated at 93 with the crossbar of the boom.

55 From the above, it will be observed that the means 36 for raising the boom 23 comprises a pair of tackles, one including the pulleys 49, 51, 61 and 63 and the cable 67, the other including the pulleys 53, 55 and 65 and cable 81. Both these tackles are powered by the fluid pressure cylinder 39 which may be termed the hoisting cylinder. When the piston rod 43 of cylinder 39 is retracted (as shown in FIG. 2), the cables 67 and 81 are 60 fully extended. When the piston rod is moved rearward (to the left as viewed in FIG. 2), the cables are hauled up to raise the boom.

65 Means is provided on the drum 3 for engagement by the bin 9 when the latter is raised to the intermediate position shown in dotted lines in FIG. 3 for effecting a pivotal connection between the bottom of the gate end of the bin (its discharge end) and the drum for tilting of the

bin on a horizontal axis extending transversely of the bin at the bottom of its gate end. As shown in FIGS. 1, 3 and 4, this means comprises a pair of eyes 95 on the drum at the bottom of the loading opening 7.

Means is provided on the vehicle for preventing it from tipping over during the lifting of the bin. As shown in FIGS. 1, 3 and 4, this means comprises a hydraulic jack generally designated 97 comprising a cylinder 99, a piston 101 movable in the cylinder, and a piston rod 103 extending from the piston 101 out of one end of the cylinder. The piston rod 103 is pivoted at its outer end upon the frame 105 of the vehicle for swinging movement on a transverse horizontal axis as indicated at 107. The outer end of the cylinder 99 has a shoe 109 pivoted thereon. The jack is adapted to swing between the raised retracted position in which it is shown in solid lines in FIG. 1 and the lowered position hanging down from the frame 105 in which it is shown in dotted lines in FIG. 1 and in solid lines in FIGS. 3 and 4. Any suitable means may be provided for holding the jack in retracted position. With the jack in its lowered position as shown in FIG. 3, fluid under pressure may be introduced into the lower end of the cylinder 99 and vented from its upper end extending the jack so that it will act as a rigid support for the side of the vehicle to prevent it from tipping over. After the lifting of the bin has been completed and the empty bin has been lowered back to the ground, fluid may be introduced into the upper end of the cylinder 99 and vented from its lower end for raising the cylinder 99, and then the jack may be swung back into retracted position as shown in solid lines in FIG. 1 so that the vehicle may be driven away without having the jack drag.

The boom cylinders 25, the hoisting cylinder 39 and the jack cylinder 99 are connected in a suitable hydraulic circuit including lines 111 and 113 connected to cylinders 25, lines 115 and 117 connected to cylinder 39, lines 119 and 121 connected to cylinder 99, and three valves 123, 125 and 127. Valve 123 controls the boom cylinders 25, valve 125 controls the hoisting cylinder 39, and valve 127 controls the jack cylinder 99. This circuit may be supplied with pressure fluid from the hydraulic power system already on the vehicle in the case of the drum-type sanitation hauling truck.

Operation is as follows:

The truck 1 is driven up alongside a bin 9 which has been rolled out to the curb C with the gate end of the bin toward the street. The jack 97 is lowered to its operating position, and then valve 127 is operated to supply fluid under pressure to the lower end of the jack cylinder 99 and to vent the upper end of this cylinder. This extends the jack and it serves as a rigid support for the side of the truck to prevent it from tipping over. The boom 23 is swung down to a position such as shown in FIG. 3, wherein the crossbar 33 extends generally centrally over the top of the bin, the crossbar being in the retracted position shown in solid lines in FIG. 3. With the boom 23 in the lowered FIG. 3 position, and with the crossbar 33 retracted, the cables 67 and 81 are fully extended. The chains 35 are then connected to the pins 19 on both sides of the bin.

Valve 123 is then operated partially to extend the plungers 31 and the crossbar 33 to a position relative to cylinders 25 such as is shown in dotted lines in FIG. 3. Since the cables are fully extended, this results in upward swinging of the boom and lifting of the bin 9 to some extent. Then the valve 125 is operated to operate the hoisting cylinder 39 to haul up the cables and swing the boom up to the dotted line position shown in FIG. 3 in which the hooks 21 on the bin engage in the eyes 95 on the drum 3. This effects a pivotal connection between the bin and the drum. Then valve 125 is operated to continue the upward swinging of the boom and valve 123 is operated further to extend the plungers 31 and the crossbar 33 to a position relative to cylinders 25

such as is shown in FIG. 4. This results in tilting of the bin as shown in FIG. 4, and the gate 15 on the bin swings open for discharging the contents of the bin into the drum 3. The empty bin may then be lowered by 5 reversing the above-described procedure.

In view of the above, it will be seen that the several objects of the invention are achieved and other advantageous results attained.

As various changes could be made in the above constructions without departing from the scope of the invention, it is intended that all matter contained in the above description or shown in the accompanying drawings shall be interpreted as illustrative and not in a limiting sense.

15 I claim:

1. In combination in a truck having a hollow body, a pair of extensible hoist arms, means pivotally mounting the inner ends of said arms on a side wall of said body, a transverse bar connecting the outer ends of said 20 extensible arms, power means for extending and contracting said arms, a hoist cable extending from said bar toward the top of the truck body, a second power means operatively connected to said cable for raising said arms, flexible members on said bar for suspending a receptacle therefrom, and abutment means on said body adapted to engage and tilt said receptacle responsive to movement of the latter by said hoisting arms.

2. In combination, a hauling vehicle having a drum provided with a side loading opening and means for 30 lifting a receptacle and tilting it to dump its contents into the drum through said opening, said means comprising a U-shaped boom having parallel extensible side arms, each of said side arms comprising a fluid pressure cylinder having a plunger movable therein, said cylinders 35 being pivotally connected at one end thereof to the vehicle for swinging movement in vertical planes at opposite sides of said opening, each of said plungers projecting out of the other end of its said cylinder, and a crossbar connecting the outer ends of the plungers;

40 means carried by the vehicle for raising the boom from a lowered position wherein a receptacle may be attached to the outer end of the boom, and means on the drum engageable by the receptacle when raised for effecting a pivotal connection between the receptacle and the drum.

45 3. The combination of claim 2 wherein the means for raising the boom comprises a pair of cables extending from the crossbar at opposite sides of said opening, and means on the vehicle for hauling up the cables.

50 4. The combination of claim 2 wherein the means for raising the boom comprises a pair of tackles including a pair of cables extending from the crossbar at opposite sides of the opening, and a fluid pressure cylinder mounted on the vehicle for powering the tackles.

55 5. The combination of claim 2 further comprising pairs of chains at opposite ends of the crossbar for attachment to a receptacle.

60 6. In combination with a drum-type sanitation hauling truck having a drum provided with a side loading opening, means for lifting an end-discharge rubbish bin and tilting it to dump its contents into the drum through said opening, said bin having at least one hook at its bottom at its discharge end, said means comprising a U-shaped boom having parallel extensible side arms, each 65 of said arms comprising a fluid pressure cylinder having a plunger movable therein, each cylinder being pivotally connected at one end thereof to the drum, each plunger projecting out of the other end of its related cylinder, a crossbar connecting the outer ends of said

70 plungers, means carried by the drum for pivotally raising and lowering said boom, and means on the drum at the bottom of said opening engageable by said hook for effecting a pivotal connection between the bin and the drum.

75

7. The combination of claim 6 wherein the means for raising the boom comprises a pair of cables extending from the crossbar at opposite sides of said opening, and means mounted on top of the drum for hauling up the cables.

8. The combination of claim 6 wherein the means for raising the boom comprises a pair of tackles including a pair of cables extending from the crossbar at opposite sides of the opening, and a fluid pressure cylinder mounted on top of the drum extending lengthwise ¹⁰ of the drum for powering the tackles.

9. The combination of claim 6 further comprising pairs of chains at opposite ends of the crossbar for attachment to a bin, the bin having pins on opposite sides ¹⁵ thereof for attachment of the chains.
